UNITED STATES PATENT OFFICE.

FRANK HOWARD MAYER, OF DENVER, COLORADO.

WASHING-MACHINE.

1,385,748.

Specification of Letters Patent. Patented July 26, 1921.

Original application filed January 17, 1920, Serial No. 352,097. Divided and this application filed April 24, 1920. Serial No. 376,271.

To all whom it may concern:

Be it known that I, FRANK HOWARD MAYER, a citizen of the United States, and a resident of Denver, in the county of Denver and State of Colorado, have invented 5 certain new and useful Improvements in Washing-Machines, of which the following is a specification.

My invention relates to improvements in 10 washing machines, and it consists in the constructions, combinations and arrangements herein described and claimed.

One of the foremost objects of my invention is to provide a washing machine with 15 a clothes cradle which is interiorly ribbed so as to produce a "wash-board" effect on the clothes, which cradle has no interior rods or other projections which would tend to cause the clothes to become entangled.

20 A further object of the invention is to provide in a washing machine, an improved cradle preferably made of strong wire mesh but given a corrugated shape for the purpose of producing a "wash-board" effect, 25 the cradle being strengthened by end crosses which have continuations running along the outside of the cradle to provide major braces at a plurality of places.

20 A further object of the invention is to provide a washing machine which includes 30 a novel construction of gearing by means of which the clothes cradle may be either continuously rotated so as to expel the water from the clothes by centrifugal action, or 35 oscillated to carry out the washing operation.

Other objects and advantages will appear in the following specification, reference being had to the accompanying drawings, in 40 which:—

Figure 1 is a longitudinal section of the improved washing machine, illustrating the cradle in side elevation, and

45 Fig. 2 is a cross section taken substantially on the line 2—2 of Fig. 1.

This is a division of my co-pending application for a patent on washing machines, filed January 17, 1920, Serial No. 352,097. Attention is directed to that application for 50 the details of the gearing illustrated in Fig. 1, by means of which the clothes cradle of the washing machine is either oscillated or continuously rotated. However, brief mention of the structural details of this gearing 55 is made below, in order that the reader may obtain a general idea as to the working of

the whole machine. Attention is first directed to

The general construction of the washing machine, 60

which is well illustrated in Fig. 2. The tub 1 is mounted upon a suitable frame 2, is provided with a lid 3 which is hinged at 4 at the front, and further provided with suitable clamping means 5, by which the lid is firmly secured in the closed opening so as to prevent water from spilling out. The purpose of hinging the lid at the front is, that if so desired, the clothes may be taken out 70 of the clothes cradle 6 and passed between the rollers of the wringer 7.

This wringer is provided merely as an auxiliary to the washing machine, and may readily be dispensed with entirely, because 75 it is one of the purposes of the invention that water shall be expelled from the washed clothes by rapidly rotating the cradle 6 and thereby drying them by centrifugal action. In case the auxiliary wringer 7 is employed, 80 the rolls are operated by pulley and belt connections 8 which are part of the driving mechanism of the improved gearing at the right in Fig. 1, the motor 9 on the back of the frame 2, being the means by which this 85 gearing is operated.

Suitable ball bearings 29 support the stub shafts 22 of the clothes cradle 6. These stub shafts include plates 18 which are secured to the end crosses 19 of the cradle, 90 this arrangement obviating the necessity of extending a shaft axially of the cradle and thereby avoiding the probability of the clothes becoming entangled and the washing function impaired as a consequence. 95

The end crosses 19 are in connection with each other by means of the bars 20, which run longitudinally of the cradle 6 on the outside. A rigid cage is thereby provided, around and over the ends of which the wire mesh cradle 6 is supported, the bars and crosses adding materially to the strength of the cradle and preventing the sagging which would otherwise undoubtedly occur. 100

A ribbed or "washboard" surface is produced by the corrugated formation of the clothes cradle 6. The cradle may be made either of heavy mesh wire or other suitable material, so long as the corrugations clearly shown in Fig. 2, are provided. Longitudinal rods or equivalent braces 21 mounted in end rings 21^a, support the body of the cradle 110

in addition to the function of the bars 20, and thus aid in preventing sagging and distortion of the wire mesh between the major supporting bars 20. A door 22^a, hinged at 5 23 and provided with suitable fastening means 24, is for the purpose of enabling the clothes to be packed inside of the cradle.

The operation

- 10 and construction of the gearing is desired to be briefly described here, in connection with the subsequent description of the construction of the washing machine. It is to be observed that the stub shaft 22 at the right of 15 the cradle 6 carries a two-diameter pinion 25, 26 which is slideable on the stub shaft so that the larger pinion 25 may engage either the mutilated internal gear section 27 or the continuous internal gear rim 28, and that 20 25 the smaller pinion 26 may either engage the mutilated external gear section 29 or be entirely free therefrom. As stated before, the construction of the gearing is illustrated and described in detail in the co-pending application above referred to, and more than a 25 general idea of the construction and operation of the gearing cannot be gotten from the present description and illustration. It can be observed, however, that the master 30 drive gear 11 is driven continuously in one direction by means of the driving connection 10 from the motor 9, and the oscillation or continuous rotation of the cradle 6 depends on whether the two-diameter pinion 35 25, 26 is at the extremity of the stub shaft 22 or moved inwardly in respect thereto. When in the former position, the oscillating motion of the cradle 6 results, while when the two-diameter pinion is in the latter position, the continuous rotation of the cradle 40 follows with the result that water is expelled from the clothes by centrifugal action.

In carrying out a washing operation, the 45 lids 3 and 22^a respectively of the tub 1 and cradle 6, are raised and the clothes packed into the cradle. The tub is filled with hot soapy water, approximately to the height indicated in Fig. 2, the drain cock 35 50 of course being closed. Normally, the two-diameter pinion 25—26 should be in the full line position in Fig. 1 so that when the electric motor 9 is started and the master drive gear 11 is continuously rotated in one direction, the mutilated gears 28 and 29 alternately engage the pinions 25 and 26 so that

the cradle 6 is rotated first in one direction then in the other. The clothes on the inside tumbling over the ribbed surface of the cradle are thoroughly rubbed without entangling. 60

After the rubbing action has continued a sufficient length of time, the operator shifts the two-diameter pinion inwardly by any suitable means, so that the large pinion 25 65 engages the continuous internal gear 28 and the continuous uni-directional rotation of the master gear 11 is transmitted directly to the cradle 6 so that it is caused to rapidly revolve in one direction. It should be first 70 explained, however, that before this is done the cock 35 is opened to let out the dirty water, clear water having been run in thereafter so as to thoroughly rinse the clothes.

It is thereafter that the cradle 6 is rapidly revolved, the water being expelled from the clothes by virtue of the centrifugal action. It is not necessary to employ the wringer 7 at all, because the clothes can be thoroughly dried by centrifugal action in 80 the manner stated, the wringer being provided merely as an auxiliary for those who may desire to use it.

While the construction and arrangement of the improved washing machine as herein 85 described and claimed, is that of a generally preferred form, obviously modifications and changes can be made without departing from the spirit of the invention or the scope 90 of the claims.

I claim:—

A washing machine, comprising a suitable tub, with end heads carrying water-tight ball bearings; a peripherally corrugated wire mesh clothes cradle mounted in the 95 tub, said cradle having end head-bracing means including integral major bracing means running longitudinally of the cradle and formed with stub axles supported in said bearing, auxiliary bracing means between the major bracing means preventing the wire mesh from sagging; a bearing structure on one head of the tub, and gearing carried by said structure and so operatively associated with the adjacent stub 100 axle to enable the oscillation of the cradle to wash clothes contained thereby when a part of the gearing is in one position, and to continuously rotate the cradle and expel the water from the clothes by centrifugal action 105 110 when said part is shifted to another position.

FRANK HOWARD MAYER.
